1

This invention relates to statistical machines. In some statistical machines it is desired that numbers sensed from a record, such as a perforated card, according to their ordinary significance be transmitted for use in the machine according to a predetermined code. With such machines it is necessary to provide a coding device adapted to translate the sensed numbers of ordinary significance into the selected code and it is an object of the present invention to provide a coding device to translate into a predetermined code numbers sensed from a record according to their normal significance.

According to the invention there is provided for a statistical machine, a coding device wherein an intermediate element of a column of intermediate elements, one for each index position representative of a number of ordinary significance in a column of a record, is settable by an impulse received as the result of the sensing of a data representation corresponding thereto in a record, each intermediate element having associated therewith a pivoted actuator movable from an active to an inactive position and controllable for movement to one of said positions by its associated intermediate element, said actuators each being associated with a predetermined one of a column of translator elements and mounted for movement into and out of operative engagement therewith when in active position, the translator elements each being connected with one of a plurality of coding elements or with a combination of said coding elements whereby on actuation of a translator element by its associated actuator the coding element or elements connected therewith is or are caused to transmit an impulse or impulses giving a code representation of a sensed number of ordinary significance.

Further according to the invention there is provided for a statistical machine, a coding device comprising sensing means to sense from a record data representations of numerals according to their ordinary significance, coding elements to transmit impulses giving a code representation of sensed numbers of ordinary significance, translator elements each representative of a number of ordinary significance and each connected with one of said coding elements or with a combination thereof to convert a number of ordinary significance into its code equivalent, an intermediate element for each translator element, the intermediate elements being settable by said sensing means, and a pivoted actuator for each translator element, the actuators each being movable from an active to an inactive position and con-

2

trollable for movement to one of said positions by its associated intermediate element and mounted for movement into and out of operative engagement with its associated translator element, whereby on movement of active actuators into engagement with their associated translator elements sensed numbers of ordinary significance are converted into their code equivalents.

Each coding element may comprise an electrical make-and-break switch controlling an electrical circuit and in one embodiment of the invention the actuators are normally in active position and the sensing means comprises sensing pins adapted to enter data representing perforations in a record, said pins being supported for axial movement in a fixed frame and each aligned with a predetermined one of said intermediate elements, and wherein a card chamber is supported by a movable frame for reciprocation towards and away from said fixed frame whereby when the chamber is moved towards said frame sensing pins failing to pass through perforations in a record set their associated intermediate elements thereby rendering inactive the actuators associated therewith. The actuators may be supported by a movable frame so disposed with relation to the carriage as to be engaged thereby and moved therewith after the carriage has moved a distance sufficient to effect the setting of the intermediate elements, whereby the active actuators are caused to actuate the translator elements associated therewith.

When the decoding device according to the invention is to be employed in conjunction with a calculating apparatus of the kind which employs electronic valves for effecting the calculations it is desired to use the minimum number of such valves for this purpose and to this end it is proposed in one embodiment of the invention to employ the known four figure code according to which all numbers of ordinary significance are coded into the code represented by the four figures 8—4—2—1, and a coding device according to the present invention may be arranged to operate according to this code.

When a calculating apparatus operates in accordance with a code the results or answers obtained by the apparatus are transmitted therefrom in code, and when it is desired to include the result in a result field of the record from which the factors for the calculation were sensed as numbers of ordinary significance the coded result must be decoded before it can be included in the result field in terms of numerals of ordinary significance. Accordingly, the invention

also contemplates a coding device according to the invention in combination with means to feed a record to the sensing means, punch mechanism to punch the result of a calculation in a record from which the sensing means has sensed the factors for the calculation, means to feed a record from the sensing means to said punch mechanism, and punch setting means including a decoding unit to receive a result transmitted thereto as impulses according to a code and to decode the impulses to impulses representative of numbers of ordinary significance, and means actuated by said last named impulses to set the punches of the punch mechanism.

In order that the invention may be more clearly understood one embodiment thereof will now be described, by way of example, with reference to the accompanying diagrammatic drawings in which,

Figures 1A and 1B together are an elevation partly in section of a sensing and punching mechanism, the sensing mechanism having associated therewith a coding device according to the invention.

Figure 2 is a view of a part of the sensing mechanism shown in Figure 1A and shows more clearly the coding device associated therewith,

Figure 3 is an end view looking in the direction of arrow A, Figure 2,

Figure 4 is a section, to an enlarged scale, on line IV—IV, Figure 1B,

Figure 5 shows, in side elevation and top plan, the arrangement of a column of decoding bars employed in conjunction with the punch mechanism, the decoding bars being shown in their normal or inactive positions, and

Figure 6 is a diagrammatic perspective view showing the manner in which the decoding bars are operated to transmit the translation of coded numbers as impulses representative of ordinary numerical significance.

Referring to the drawings perforated record cards are fed from the bottom of a pile contained in a magazine 23, Fig. 1A, by a picker 21 mounted for reciprocation beneath the magazine. The picker is oscillated by arms 22 pivoted to the machine frame 23, the arms being oscillated about their pivot 24 by a link 25 actuated by an eccentric 26 mounted on the main shaft 27 of the machine. The main shaft 27 is rotated in any suitable known manner, such for example as by an electric motor and clutch mechanism of known construction.

As each card is fed from the bottom of the magazine it is received between feed rollers 28 which deliver it into a card chamber 29 forming part of a sensing device. The leading edge of the card entering the card chamber is arrested by a locating stop 30 which is reciprocated into and out of the path of the cards by a cam 31 and link mechanism 32, 33, the cam 31 being mounted on an auxiliary shaft 34 driven through the intermediary of gears 35, 36, 37 at the same angular speed as that of the main shaft 27.

The card chamber comprises a top plate 38 and a bottom plate 39 each of which is apertured, the apertures in the two plates being aligned so that sensing pins 40 can pass through the aligned apertures and an aperture is provided for each data index position on a record card. The apertured plates 38, 39 are spaced apart from each other by a distance sufficient to accommodate the thickness of a record card and the plates are mounted on a carriage 41

which is guided for vertical reciprocation between the side frames of the machine. Reciprocation of the carriage is effected by a cam 42 mounted on the auxiliary shaft 34 and a pivoted link 43 connects the carriage with the cam. The end of the link which is connected to the carriage is preferably mounted on an eccentric pin 44 to permit fine adjustment of the stroke of the carriage.

Above the card chamber there is disposed a number of sensing pins 40 mounted for axial movement in a fixed frame comprising horizontal guide plates 45 and 46, each pin having a collar 47 to determine the extent of downward movement of the pin by engagement with the lowermost guide plate 45. If desired, a sensing pin may be provided for each card index position or sensing pins may be provided only for certain card columns in certain predetermined fields of a card.

The sensing pins 40 are arranged in columns as is well understood in the art, one such column of pins being shown in Figure 2. As the details for each column are the same, as will be well understood, only one such column and its associated mechanism will be described in detail herein although in Figure 3 there is shown a cross-section of the machine employing eight columns of sensing pins and associated mechanism.

To facilitate the selection of fields to be sensed the sensing pins and guide plates may be supported by side plates 48 slidably mounted on bars 49 extending between the side frames of the machine.

The upper ends of the sensing pins are each connected with an intermediate element comprising a rigid connection wire 56 and the upper and lower ends of the connection wires pass through horizontal guide plates 51, 52, 53, Figure 3, so that the connection wires can be reciprocated axially as a result of the movement of the sensing pins. Each connection wire is provided with a collar 54 and a spring 55, the springs acting against the collars 54 and the upper guide plate 53 and tending to urge the connection wires and the sensing pins downwards.

The plate 53 forms part of a movable frame 56 slidable in guides 57 secured to fixed side frames 58 supporting the coding mechanism. From the carriage 41 there extends upwards two arms 59 having at their upper ends adjustable members 60. When the carriage is in its lower position, as indicated in Figure 3, the adjustable members 60 are spaced from the lower ends of the movable frame members 61 which slide in the guides 57. Thus on upward movement of the carriage 41 the card supported in the card chamber 29 moves into sensing relation with the sensing pins 40 and those pins which are aligned with perforations in the record card pass through the card so that such sensing pins are not raised axially and consequently do not effect axial movement of the intermediate elements 56 associated therewith. On the other hand those sensing pins which are not aligned with the perforations in the card are engaged by the card as it is raised and are moved axially upwards thereby effecting upward movement of their associated intermediate elements 56 against the action of springs 55. When the sensing of the card has been so effected the carriage is raised to the position at which the adjusting members 60 thereon engage the lower ends of the mov-

able frame members 61 and continued upward movement of the carriage 41 effects upward movement of the frame 56.

Secured to the plate 53 is a plurality of actuators 62, one for each intermediate element 50, each of which is pivoted at 63 to a support 64 secured to the plate 53. Each actuator 62 is provided with two shoulder members 65, 66 of which the shoulder 65 is engaged by its associated intermediate element 50. The shoulder 66 is connected with a spring 67 which urges the actuator to the position shown in Figure 3 and in which position the shoulder 66 is engaged with the undersurface of an overturned portion 68 forming part of the support 64. As shown in Figure 3 each of the actuators 62 is in its normal or active position in which position its upper end is aligned with the lower end of a translator element 69, shown in the drawing as a pin adapted to operate Bowden wires 70 associated therewith.

With the arrangement as just described, if, during the sensing of the record, a sensing pin 40 passes through a data indicating perforation in the record the intermediate element 50 associated therewith is not moved upwards and the actuator 62 associated with that particular intermediate element remains in the active position shown in Figure 3 so that on upward movement of the frame 56 it engages the lower end of the translator element 69 and actuates that element thus in turn operating the Bowden wire or wires 70 associated therewith. If, however, a sensing pin 40 does not pass through a data indicating perforation in the card it is raised axially thereby moving its associated intermediate element 50 upwards and rocking the actuator 62 associated therewith about its pivot 63 so that the upper end of the actuator is moved to its inactive position in which position it is out of alignment with the lower end of its associated translator element 69. Thus on upward movement of the frame 56 the inactive actuators will be moved past the translator elements associated therewith and will not effect actuation thereof.

As can be seen by reference to Figures 2 and 3 the translator elements 69 extend downwards from holders 71 each of which houses the lower end of one or more of the Bowden wires 70. From Figure 2 it will be seen that for each column of sensing pins 40 representing the numbers 1 to 11 according to their ordinary signification there is provided a holder 71. In Figure 2 these holders are numbered 1 to 11 in the order in which these numbers are arranged in a column on a card.

Above the holders 71 and supported between plates 72 and 73 are coding elements 74 in which the upper ends of the Bowden wires terminate. From Figure 2 it will be seen that for a single column of holders 71 there is provided four associated coding elements 74. The coding elements 74 are to represent in code sensed numbers of ordinary significance, the code employed being the known code according to which numbers of ordinary significance are translated into terms of the figures 8-4-2-1.

Associated with the upper ends of the Bowdens in the code elements 74 is a plate 75 from which a stem 76 extends upwards and is located in a cylindrical contact member 77, such contact member comprising conductor elements 78 and 79 and a contiguous insulator element 80. The cylindrical contact member 77 is fitted over the upper end of the stem 76 to be freely rotatable about its longitudinal axis and the contact mem-

ber is guided for axial movement in insulating bushes 81, Figure 2, supported in a conductor plate 81a, the contact member being axially movable in response to axial movement of the stem 76. The plate 81 is mounted on bars 82 supported by members 83 which are secured to the side frames 58. The cylindrical contact members 77 are urged towards the stem 76 by springs 84.

10 Contact members 85, each formed as a leaf spring depending from a plate 86, engage with the cylindrical contact member 77. The plate 86 is formed from insulating material and, as shown in the drawings, is supported by the side frames 58. The upper ends of the contact members 85 are connected with terminals 87 while the lower or free ends of the contact members each normally engages the peripheral surface of the insulator element 80 of its associated contact member 77.

15 Wear on the cylindrical contact members is substantially even around the peripheral surface thereof because due to the cylindrical contact members being freely rotatable about their longitudinal axes the contact members tend to rotate as a result of vibrations of the machine thus presenting different portions of their peripheral surfaces to the portions of the contact members 85 which engage therewith.

20 The terminals 87 are connected by wires, not shown, to an electrical calculating apparatus, not shown, adapted to operate according to the above mentioned four figure code and thus when contact member 77 is raised axially on receipt of an impulse from its associated coding element 74 its conductor element 78 is moved into engagement with its co-acting contact member 85 so that an electrical impulse is transmitted to the calculating apparatus, such electrical impulse or impulses representing a sensed number of ordinary significance according to the said four-figure code.

25 As has been mentioned above, the coding device now being described is adapted to translate numbers of ordinary significance from 1 to 11 into the 8-4-2-1 code and in Figure 2 the contact members 77 associated with the four coding elements have been numbered respectively 8, 4, 2, 1.

30 The numbers 1 to 11 are represented in the 8-4-2-1 code as follows:

The code equivalent of 1 is 1.

The code equivalent of 2 is 2.

The code equivalent of 3 is 1-2.

The code equivalent of 4 is 4.

35 The code equivalent of 5 is 1-4.

The code equivalent of 6 is 2-4.

The code equivalent of 7 is 1-2-4.

The code equivalent of 8 is 8.

The code equivalent of 9 is 1-3.

40 The code equivalent of 10 is 2-3.

The code equivalent of 11 is 1-2-3.

45

50 Accordingly, as is illustrated in Figure 2, the Bowden wires 70 connect the translator elements 69 to the code elements 74 in this manner, for example, a single Bowden wire 70 connects the translator element representative of ordinary number 8 with the coding element representing number 8 and the translator element representative of the ordinary number 7 is connected by three Bowden wires to the combination of coding elements representing numbers 1-2-4.

55 After the carriage 41 has been raised to effect actuation of the translator elements 69 it is lowered to the position at which the card chamber

29 receives a record from the magazine 20 and the sensed record is then fed out of the card chamber by feed rollers 88, 89 which feed it into a second card chamber 90, Figure 1A, forming part of a punch unit. The record is arrested in the chamber 90 by a vertical reciprocating stop 91 operated from a cam, not shown, on the main shaft 27 through the medium of rocking arm 92 and rod 93 on the stop 91.

The card chamber of the punch unit is mounted for vertical reciprocation with a carriage 94 and comprises upper and lower die members 95, 96. Punches 97 are provided in guides 98 and extend into the upper die member, being freely mounted for axial movement relative to their guides. Above the punches is disposed a set bar unit S. B. U. of known construction, the set bars 99 being arranged in columns to co-operate with the punches and provided with locking means to retain the bars in set position together with restoring means for restoring the bars after a punching operation has been effected.

In Figure 1A one column of set-bars 99 is shown, as will be well understood, together, in Figure 1B, with the decoding mechanism for that column. Figure 4, however, is a cross-section of the machine and shows a part of each of six columns, it being assumed for the purposes of this specification that the punch unit is to be capable of punching a six-figure answer or result in the result field of a record.

Above the set bars 99 and aligned therewith are selector pins 100, Figure 1B, mounted to be axially movable between horizontal guide members 101 and 102, the selector pins being urged by springs 103 away from the upper ends of the set bars. The upper end of each of the selector pins is connected with a rigid connection wire 104, the upper ends of the wires 104 being located between guides 105, 106 for engagement by translator elements 107. Each translator element represents a number according to its ordinary significance and the translator elements are arranged in columns as shown in Figure 1B, a translator element 107 being provided for each of the numbers 1 to 11 inclusive.

Associated with each column of translator elements 107 is a set of decoding bars, the set consisting of four bars 108, 109, 110 and 111 associated respectively with electro-magnets 112, 113, 114 and 115. The electro-magnets are adapted to be energised by impulses received from the calculating apparatus in accordance with the result of the calculation effected by the calculating apparatus. The result transmitted from the calculating apparatus to the electro-magnets is according to the 8-4-2-1 code described above and the electro-magnets in Figure 1B are identified according to the code figure which they represent.

Each electro-magnet is provided with an armature 116 from which a pin 117 extends laterally and is engaged in a slot 118 formed in one end of its associated decoding bar. The de-coding bars are supported for length-wise movement in brackets 119 and 120 secured to the side frames 121 of the punch unit. When an electro-magnet is energised it moves its associated de-coding bar lengthwise for a predetermined distance, to the right as viewed in Figure 1B. At the end of its stroke the de-coding bar is retained in its set or active position by a latch 122 pivoted at 123 to a bracket 124 secured to the side frames 121. The latch is urged downwards about its pivot by a spring 125 so that when the de-coding bar is

moved to active position the latch is engaged in a notch 126 formed in the upper edge of the decoding bar at the right hand end thereof as viewed in Figure 1B.

5 The construction of the de-coding bars is best seen in Figure 5 from which it will be observed that each of the bars is provided with a number of obstructing elements 127 and a number of guides 128 formed as grooves each representative of a number represented by one of the translator elements 107 in a column. To facilitate the understanding of the arrangement of the decoding bars each of the bars in Figure 5 has its guides numbered to indicate with which of the translator elements it is to co-operate.

From Figure 5 it will be seen that each decoding bar has the same number of guides 128 and that each has a guide to co-operate with a predetermined one of the translator elements. The 15 relative disposition of the guides 128 in the decoding bars is such that when the bars are in their normal or inactive position, that is as shown in Figure 1B, no four of the guides of like denominations are in complete alignment and it is 20 at that time not possible for the tongues 129 on the translator elements 107, Figure 4, to pass therethrough so that each of the translator elements 25 of a column are prevented from being moved downwards by the means to be described below.

As can be seen from Figure 5, the arrangement of the guides 128 on the respective bars 108, 109 30 110 and 111 is such that when the electro-magnet associated with a particular bar is energised, thereby moving that bar to the right as viewed in Figure 1B (to the left as viewed in Fig. 5), a particular guide 128 on that bar is moved into alignment with a guide of corresponding numeric value in each of the other three bars of corresponding denomination. Thus, when the translator element 107 to co-operate with the guides of that denomination is moved downwards it can pass through the aligned guides in the four bars and into engagement with the upper end of its associated connection wire 104 thereby imparting an impulse to that connection wire to effect the setting of the corresponding set bar 35 99 of the set bar unit in readiness for a punching operation.

As an example of the manner in which the decoding bars operate let it be assumed that the electro-magnet 112, representing the code number "8," has been energised the electro-magnets 113, 114, and 115 not being energised. The decoding bar 108 will be moved to the right, as viewed in Figure 1B, and retained in active position by its latch 122. In this position of the bar 108 the number "8" guide 128, see Figure 5, is in alignment with the number "8" guides formed in the bars 109, 110 and 111. Thus, on downward movement of the number "8" translator element, the element will pass through the number "8" guides in each of the de-coding bars and will effect the setting of the number "8" set bar in the 40 set bar unit.

As a further example let it be assumed that in the column under consideration impulses have been received from the calculating apparatus by each of the electro-magnets 113, 114 and 115, the electro-magnet 112 remaining inactive. When this occurs the bars 109, 110 and 111 are each moved to their active position, in which they are latched, and this movement of the bars causes the number "7" guides in each of these bars to 45 70 75 be moved into alignment with the number "7"

guide in the bar 108 which has not been moved from its normal or inactive position. Consequently on downward movement of the translator elements for this column each of the elements will be arrested by the obstructing portions of the bars, with the exception of the number "7" translator element which has a free passage through the aligned number "7" guides in each of the four bars.

As a further example let it be assumed that the electro-magnets 113 and 115 receive impulses from the calculating apparatus so that only the bars 109 and 111 are moved to the right, as viewed in Figure 1B, to their active positions. When this occurs the number "5" guides in bars 109 and 111 are moved into alignment with the number "5" guides in the bars 108 and 110 which have not been moved from their normal or inactive positions. Thus, on operation of the translator elements associated with this column the only element to receive a free passage is the number "5" element which can pass through the aligned number "5" guides in each of the four de-coding bars.

The translator elements 107 are supported in a movable frame 130 which is reciprocated vertically by a cam, not shown, on the main shaft 27. The upper ends of the translator elements pass through guide plates 131 secured to the movable frame and the lower ends of the translator elements are guided in a slotted plate 132 also carried by the movable frame 130. Each translator element 107 is urged downwards by a pin 133 and spring 134, the pin being provided with a head which engages against a shoulder on the translator element. Each translator element has formed on the edge thereof opposite the edge in which the tongues 129 are formed, a projection 135 for co-operation with a shutter 136, the shutter extending across the column of translator elements 107 as shown in Figure 1B. The shutter is pivoted at its ends, as indicated at 137, to side plates 138 movable with the frame 130. A spring 139 urges the shutter to the position shown in Figure 4 in which position its lower end is moved outwards away from the projection 135 and is arrested by a stop 140.

Assuming that at least one of the de-coding bars for the column has been moved to its active position, when the frame 130 is moved downwards each of the translator elements 107 with the exception of the one which is free to pass through its aligned co-operating guides 128 in the de-coding bars is arrested by the obstructing portions formed on the de-coding bars. This is diagrammatically illustrated in Figure 6.

From the drawings, it will be seen that before the translator elements can engage the rigid connection wires 104 they are movable through a predetermined distance and during this movement those translator elements whose movement is obstructed by the de-coding bars move upwards in relation to the descending frame so that the upper end portions 141 of the translator elements engage the inturned top portion 142 of the shutter 136 thus rotating the shutter in a clockwise direction, as viewed in Figure 4, about its pivots 137. By the time that the lower end of the shutter is moved inwards the projections 135 on the translator elements whose movement has been arrested are positioned above the inturned portion 143 at the lower end of the shutter. The translator element which has been selected for operation however, that is the one which is to be moved through the de-coding bars, has not moved

5 relatively to the shutter so that the inward movement of the shutter brings the lower portion 143 thereof into engagement with the selected translator element just above the projection 135 thereon. Accordingly during the continued downward movement of the frame the shutter acts as a driving member, engaging behind the projection 135 on the selected translator element and positively moving it downwards through the aligned slots in the de-coding bars and into engagement with the upper end of the rigid connection wire 104 associated therewith so that the latter is moved downwards and effects the setting of the appropriate set bar 99 in the set bar unit.

10 The de-coding bars which have been moved to their active positions are retained in this position by the latches 122 until the frame 130 has been raised to restore the translator elements 107 to their normal or starting position and thereafter the active de-coding bars are restored to inactive position by a vertical reciprocable restoring plate 144 the plate being reciprocated by a lever 145 operated from a cam, not shown, on the main shaft 27. The restoring plate 144 is provided with a slot 146 for each of the latches 122 and during the restoring movement the restoring plate is moved downwards so that the upper edges of the slots engage the tails of the latches 122 thus lifting the latches out of the notches 126 formed in the active de-coding bars. The de-coding bars are then restored to inactive position by the springs 147 on the electro-magnets.

25 As described above, it has been assumed that the de-coding unit is to operate only in respect of decimal problems but if it is desired that the mechanism be employed to decode sterling problems a further electro-magnet 148 is provided and the armature of this electro-magnet is connected 30 with a member 149 connected in turn to a further de-coding bar 150, see Figure 4, to co-operate with the vertical guide formed in the bar 150 an additional tongue 151 is formed on the translator element representing tens of shillings. Thus, if 35 in Figure 4 it is assumed that the de-coding unit shown therein is adapted for de-coding sterling problems the two translator elements at the extreme right of the figure represent decimal fractions of a penny, the third translator element 40 from the right of the figure represents pence, the fourth element represents shillings, the remaining two translator elements represent respectively units of pounds and tens of pounds.

45 As the result or answer is to be punched in a specific field of the card it is not necessary to provide an electro-magnetic, de-coding bars and translator elements for each card index position but only sufficient columns of electro-magnets, de-coding bars, and translator elements for a field of predetermined capacity. Accordingly the 50 electro-magnets, de-coding bars and associated translator elements are formed as a unit and mounted on bars 152 extending between the frames 121 so that by sliding the unit lengthwise 55 of the bars selection of the result field with respect to a record can be obtained.

60 After a card in the chamber 90 has been raised and punching effected therein the carriage 94 is again lowered and the card is fed out of the card chamber 90 between rollers 153 which deliver the card into a magazine 154.

65 In order that the operation of the devices according to the invention may be clearly understood, the function thereof will now be described 70 on the assumption that a card fed to the sensing

11

chamber contains a multiplicand 987 and a multiplier 456 which are to be multiplied together in an electrical calculating apparatus, the result or answer being transmitted from the calculating apparatus in code to the punch unit where the result is de-coded and is punched in a result field of the card from which the factors have been sensed.

The card after being fed into the sensing chamber 29 is raised into engagement with the sensing pins 47 and all the pins, with the exception of those which sense the factors given above, are raised by the card so that their associated intermediate elements 59 are lifted to rock their associated actuators 62 to their inactive positions, in which positions they are out of alignment with their associated translator elements 69.

Taking first the multiplicand 987 sensed from the card, in the units column the number "7" translator element receives an impulse from its actuator 62 and through the Bowden wires 70 sends impulses to each of the code elements 1-2-4. Accordingly three electrical impulses are sent via the switches 85 to the calculating apparatus to represent the sensed number "7." In the tens column the translator element representing the sensed number "8" sends a single impulse to the code element "8" thereby initiating a single electrical impulse for transmission to the calculating apparatus representative of the sensed number "8." In the hundreds column the translator element representing the sensed number "9" sends impulses to the number "1" and the number "3" code elements so that two electrical impulses are sent to the calculating apparatus to represent the sensed number "9."

Having regard to the multiplier 456 sensed from the card, electrical impulses are transmitted to the calculating apparatus as follows: the units multiplier "6" is represented by two electrical impulses initiated by the number "2" and number "4" code elements in that column, the tens multiplier "5" is represented by two electrical impulses initiated by the number "1" and number "4" code elements in that column and the hundreds multiplier "4" is represented by a single electrical impulse initiated by the number "4" code element in that column.

When the calculation has been completed the answer obtained by multiplying 987 by 456 is 453,072 and this result is transmitted to the punch unit in terms of the 8-4-2-1 code as follows: the "2" is transmitted to the units column of the punch unit as an electrical impulse to the number "2" electro-magnet 114, the number "7" is transmitted to the tens column electro-magnets as three electrical impulses, one to the electro-magnet 115, one to the electro-magnet 114, and one to the electro-magnet 113. In the hundreds and thousands columns none of the electro-magnets are energised as in each of these two columns the resultant figure is zero, but in the tens of thousands column the "5" is transmitted to the electro-magnets associated therewith as two electrical impulses, one to the electro-magnet 115, and the other to the electro-magnet 113. In the hundreds of thousands column the "4" to be registered therein is transmitted as a single electrical impulse to the electro-magnet 113 of that column.

On energisation of the electro-magnets the de-coding bars associated therewith are moved to the right, as viewed in Figure 1B, and are retained in their set positions by the latches 122. Thus on downward movement of the frame 130, in the units column of translator elements the

12

number "2" element is permitted to be moved downwards into engagement with its corresponding connection wire 104, and in the tens column only the translator element representative of "7" is selected. As zeros appear in the hundreds and the thousands columns of the answer none of the translator elements 167 corresponding to these columns are permitted to descend with the frame 130 as none of the decoding bars associated therewith is active, and in the tens of thousands and hundreds of thousands columns only the translator elements representative of the numerals "5" and "4" respectively are permitted to descend with the frame. By the operation of the selected translator elements the result 450,072 is transmitted to the set bar unit S. B. U. and when the card, which by now is in the card chamber 36 is moved upwards together with the punches 97, the selected set bars 99 cause the appropriate punches to punch the answer 450,072 in the result field of the card, although only the positive digits 4, 5, 7, and 2 are actually punched in the card.

After the set bars 99 of the set bar unit have been set the frame 130 is raised and the active de-coding bars are restored to inactive position as above described, and after the answer has been punched in the card the card chamber is again lowered so that the card therein is fed out of the chamber and is delivered into the receiver 154.

Although in the foregoing description the coding and de-coding mechanism has been described with reference to its application to coding and de-coding according to the 8-4-2-1 code it will be understood that, if desired, the mechanism herein described can be employed for coding and de-coding according to other forms of code.

It should also be understood that although in the coding device it has been found convenient to employ Bowden wires as the means of transmitting impulses from the translator elements 69, the impulses could, if desired be transmitted electrically. Further, it will be understood by those skilled in the art that there may be employed sensing means other than sensing pins as described herein.

I claim:

1. In a record controlled statistical machine of the class described, record sensing means including a separate sensing element for each value designating index position of said record being sensed and a carriage for reciprocating a record into sensing relation to said sensing elements, a plurality of coding elements controlled by said sensing means and fewer in number than said sensing elements, each of said coding elements being singly settable to represent the value associated with a predetermined one of said sensing elements and jointly settable in combination with one or more other coding elements to represent in combinational code the values associated with all of said sensing elements, and means operatively interposed between said sensing elements and said coding elements for selectively actuating the coding element or elements representative of the value detected by said sensing means, said interposed means including a separate actuator associated with each sensing element and interponents extending from each actuator to the coding element or elements settable to represent the value associated with the related actuator, each actuator being pivotally mounted to swing from an active to an inactive

setting under control of the single sensing element associated therewith, each actuator also reciprocally mounted to move into and out of operative position relative to the interponents associated therewith, said actuator when in active setting and moved to said position operatively engaging said interponents to actuate the coding element or elements representative of the value associated with the individual sensing element controlling said actuator.

2. For a statistical machine, a coding device comprising sensing means to sense from a record data representations of numerals according to their ordinary significance, coding elements to transmit impulses giving a code representation of sensed numbers of ordinary significance, translator elements each representative of a number of ordinary significance and each connected with one of said coding elements or with a combination thereof to convert a number of ordinary significance into its code equivalent, an intermediate element for each translator element, the intermediate elements being settable by said sensing means, a reciprocally mounted pivoted actuator for each translator element, the actuators each being movable about their pivotal axis from a normally active position to an inactive position and movable to the inactive position by its associated intermediate element, and means operable independently of the setting of said intermediate elements by said sensing means to reciprocate the actuators into and out of operative relationship to their associated translator elements, whereby on movement of said actuators into said operative relationship the actuators in active position engage with their associated translator elements to convert numbers sensed according to their ordinary significance into their code equivalents.

3. A coding device according to claim 2, wherein the actuators are normally in active position and the sensing means comprises sensing pins adapted to enter data representing perforations in a record, said pins being supported for axial movement in a fixed frame and each aligned with a predetermined one of said intermediate elements, and wherein a card chamber is supported by a carriage for reciprocation towards and away from said fixed frame whereby when the chamber is moved towards said frame sensing pins failing to pass through perforations in a record set their associated intermediate elements thereby rendering inactive the actuators associated therewith.

4. A coding device according to claim 3, wherein the actuators are supported by a movable frame, said movable frame being so disposed with relation to said carriage as to be engaged thereby and moved therewith after the carriage has moved a distance sufficient to effect the setting of the intermediate elements, whereby the active actuators are caused to actuate the translator elements associated therewith.

10 5. In a device of the class described, translator elements, sensing pins, actuator elements between the pins and the translator elements and normally in active position, a movable card chamber for advancing a card into sensing relation with 15 the pins, means operated by the pins, as the chamber first advances, to move certain actuators to inactive position, and means independent of said pins and made effective by further advance of the chamber to cause the actuators which are 20 in active position to lift the translator elements associated therewith.

6. In a device of the class described, a plurality of translator elements to be moved, a corresponding number of sensing pins to be advanced towards said translator elements, a corresponding number of actuator elements each having a pivoted portion disposable in active and inactive positions with respect to a translator element and normally disposed in active relation thereto, a frame supporting said actuator elements, a card chamber, means for moving said chamber toward said sensing pins, means connecting the pins with respective actuators to tilt said pivoted portions to inactive position as the chamber is elevated, and means associated with the chamber-moving means and the frame supporting the actuators to lift the frame after the tilting of the actuators has taken place to positively lift the pivoted portion of the untilted actuators into contact with the associated translator elements and lift the same.
